[57] CLAIM

The ornamental design for a seat, as shown and described.

DESCRIPTION

FIG. 1 is a front perspective view of a seat in the form of a loveseat according to our new design.

FIG. 2 is a front elevational view of a seat in the form of a loveseat.

FIG. 3 is a top plan view of a seat in the form of a loveseat.

FIG. 4 is a rear elevational view of a seat in the form of a loveseat.

FIG. 5 is a side elevational view of a seat in the form of a loveseat, the opposite side being a mirror image thereof.

FIG. 6 is a front perspective view of a seat in the form of a sofa according to our new design.

FIG. 7 is a front perspective view of a seat in the form of a chair according to our new design.

FIG. 8 is a front elevational view of a seat in the form of a chair.

FIG. 9 is a top plan view of a seat in the form of a chair.

FIG. 10 is a side elevational view of a seat in the form of a chair, the opposite side being a mirror image thereof.

FIG. 11 is a rear elevational view of a seat in the form of a chair.

FIG. 12 is a front perspective view of a seat in the form of a chair shown in an alternate position.

FIG. 13 is a top plan view of a seat in the form of a chair shown in an alternate position; and,

FIG. 14 is a side elevational view of a seat in the form of a chair shown in an alternate position.

The side views of FIG. 6 are like that shown in FIG. 5.

The rear of FIG. 6 has not been shown and forms no part of the claimed design.

The broken line showings of an adjustment handle, a base and legrest extension/support members are for illustrative purposes only and form no part of the claimed design.
